WIRE WORKING TOOL

Mason Foshee, Kissimmee, Fla.

Application September 23, 1937, Serial No. 165,410

5 Claims. (Cl. 140—117)

This invention relates to improvements in wire working tools and more particularly to a tool for carrying out one or all of the operations of bending, coiling and sealing wire fastenings for shipping containers generally.

In explanation of the tool of the present invention and the use for which intended, shipping containers of the wire-bound type generally utilize binding wires which are secured to and extend about the container, the ends of the wires being connected or fastened together following the packing operation prior to shipment. The present invention provides in a unitary tool means for bending one or both of the ends of the binding wires into loop or bight formation. Further, the tool provides means for coiling an end of the binding wire whereby to form a female element of the fastening, either prior to association with the related male loop or after such association, in which latter event the wire is coiled directly about the male loop. Finally, the tool of the present invention provides means for hooking and thereby sealing one element, such as the male loop, of a fastening over the related female element which may be in either loop or coil form.

Other objects will be in part obvious and in part hereinafter pointed out in connection with the following analysis of this invention wherein is illustrated an embodiment of the invention in detail.

In the drawing—

Fig. 1 is a section through the tool of the present invention;

Fig. 2 is a view illustrating the use of the tool as a wire bender or looper;

Fig. 3 is a view illustrating the use of the tool as a coiler;

Fig. 4 is a part view of the tool illustrating its use as a hooker or sealer.

Referring now to the drawing wherein like reference characters designate like parts throughout the several views, the tool is constituted by a three-armed body portion generally designated 10, of which the wire bending arm 11, the hooking arm 12, and the tubular arm portion 13 may be cast integrally in the form of a T.

Referring to the bending arm 11, the end face thereof is provided with a transverse notch 15 of depth and width as to receive a wire to be bent, with some degree of clearance. Preferably flat faces 16, 17 are formed at the end of the arm, these faces extending generally parallel to each other and to the sides or walls of the notch 15.

In the operation of the tool as a bender, the tool is placed so that its notch 15 receives the wire to

be bent as indicated at 26, Fig. 2. While maintaining the axis of the arm 11, the tool may thereupon be turned 180° whereupon the wire 20 is bent back on itself to form an open-ended loop or bight, the turn or bend being effected with a small radius, so that the legs of the resulting wire formation extend generally parallel and are slightly spaced. The provision of the two flat faces 16 and 17 at the arm end permits the tool to be used either left or right handed.

Referring to Fig. 2, the tubular arm portion 13 of the tool body is interiorly threaded to receive the threaded end of a tubular shank 22. The secured end of the shank terminates short of the base of the recess or cavity formed in the portion 13 and loosely restrained between the cavity base and the secured end of the shank is the head 23 of a mandrel 24. The loose mounting of the mandrel permits the same to be freely rotated and provides for a minor degree of lateral or rocking movement for the purpose to be described.

The lower edge of the shank is inclined as at 26, and the long side of the shank is provided with an offset notch 27, a wall of which is extended to form a wire retaining hook 28. The depth of the notch 27 is such that a wire seating on its bottom portion engages and bears against the lower edge of the short side of the shank, so that the depth of the notch 27 is slightly greater than the diameter of the wire to be coiled.

In operation of the tool as a coiler, the tool is positioned as illustrated in Fig. 3 with the wire 30 to be coiled seating in the offset notch 27 and bearing against the opposite edge of the short end of the tubular shank. The hook 28 functions to retain the wire properly seated in notch 27.

Rotation of the tool about the axis of the shank 22 causes the wire to be coiled progressively on the mandrel 24, the turns or convolutions of the coil being formed by the length of wire initially extending between the point of contact where the hook 28 first engaged the wire and the terminal end thereof. Thus two full rotations of the tool will result in the formation of a coil of two convolutions. Inasmuch as the inner diameter of the coil so formed must be such as to permit a male loop to extend therethrough to effect the fastening operation contemplated, the diameter of the mandrel 24 which controls the inner diameter of the coil will be somewhat greater than the width of the male loop to be projected through the coil.

A further operation permitted by the coiling arm of the tool is that of coiling a wire directly on a male loop, such as indicated at 32. To effect

this operation, the loop 32 is projected into the tubular shank 22, the inner diameter of the shank being such as to permit this insertion with suitable clearance. The lateral movement permitted 5 the mandrel also aids in the insertion and compensates for any irregularities in the width of the loop. With the loop so inserted in the mandrel as indicated at 32, Fig. 3, and with the wire to be coiled thereabout properly seated in the 10 offset notch 27, turning movement of the tool about the axis of shank 22 operates to coil the wire 30 directly on the loop 32.

Referring now to the tool arm 12, the outer end thereof is tapered and narrowed as at 35 to provide a pointed tang end. In operating the tool 15 as a hooker or sealer, the tang end is projected through the end of a male fastener loop which has been threaded through or otherwise cooperated with the female loop or coil. Thereupon the 20 pointed end of the tang is anchored against the adjacent surface of the front section of the container, and the arm 12 operated as a lever to cause the nose or projecting end of the male loop to be hooked over the related female fastener element. By exerting the proper degree of hooking 25 or bending pressure on the arm, the bent-over end of the male loop may be brought into close proximity with the front face of the container.

The tool as described above may be constructed 30 at a low cost and by actual experience has been found to perform in efficient manner the operations for which intended.

As many changes could be made in carrying out the above construction without departing 35 from the scope of the invention, it is intended that all matter contained in the above description or shown in the accompanying drawing shall be interpreted as illustrative and not in a limiting sense.

40 I claim:

1. A wire-working tool including a cross portion and a tubular shank portion, a mandrel carried by the shank portion and extending beyond the end thereof, the end face of the shank portion being inclined and having an offset notch 45 formed in the long side of the shank portion, the bottom of the notch being in substantial alignment with the opposite, short side of the shank portion, the notch being adapted to receive the wire for coiling on the mandrel.

2. A wire-working tool including a cross portion and a tubular shank portion, a mandrel loosely carried by the shank and extending be-

yond the end thereof, the end face of the shank portion being inclined and having an offset notch formed in the long side of the shank portion, the bottom of the notch being in substantial alignment with the opposite, short side of the shank portion, a defining side of the notch being extended to form a wire retaining hook, the notch being adapted to receive a wire for coiling on the mandrel. 5

3. A wire working tool including a tubular shank portion, a mandrel carried by the shank portion and extending beyond the working end thereof, the mandrel being of lesser diameter than the interior diameter of the shank portion, and means extending from the working end of the shank portion adapted to engage against the free end portion of a wire disposed transversely of the mandrel and bearing thereagainst, said means being operative upon rotation of the tool about its axis to coil progressively the free end of the wire on the mandrel. 10

4. A wire working tool including a handle portion, a depending tubular shank portion, and a mandrel operatively disposed within the shank portion and extending beyond the working end thereof, the interior diameter of the shank portion being sufficient to receive a generally parallel-sided loop of wire, and the working end of the shank portion being provided with means adapted to engage a length of wire disposed 15 transversely of the mandrel and bearing thereagainst, said means being operative upon rotation of the tool about its axis to coil progressively the length of wire on the mandrel and about a loop received within the tubular shank portion. 20

5. A wire working tool including a handle portion, a depending tubular shank portion, and a mandrel loosely carried by the shank portion and extending beyond the working end thereof, the interior diameter of the shank portion being sufficient to receive a generally parallel-sided loop of wire, and the diameter of the mandrel being substantially less than the inner diameter of the shank portion, and means extending from the working end of the shank portion adapted to engage against a length of wire disposed 25 transversely of the mandrel and bearing thereagainst, said means being operative upon rotation of the tool about its axis to coil progressively the length of wire on the mandrel and about a loop received 30 within the tubular shank portion. 35
